FEEDING MECHANISM FOR GRINDING MILLS

John Holland-Letz, Crown Point, Ind., assignor to The Letz Manufacturing Company, a corporation of Indiana

Application August 6, 1930. Serial No. 473,305

6 Claims. (Cl. 146—119)

The present invention relates to grinding mills generally, but more particularly to a feeding attachment therefor, for the feeding of hay and similar materials to the cutter head of the grinding mill.

The primary object of the present invention is to provide a novel and improved feeding mechanism attachment for grinding mills and the like, which is adapted to cooperate with the conveyor 10 apron of the feeding mill so as to more positively insure the feeding of fluffy material such as hay and the like, in proper volume to the cutter head of the mill.

A further object of the invention is to provide 15 a novel and improved feeding attachment for a grinding mill which is adapted to be used in combination with a floating endless type feed belt which is located over the delivery end of the horizontal conveyor of the mill.

20 A still further object of the invention is to provide a novel and improved feeding mechanism for a grinding mill, in which two revolving tined members are located on the opposite sides of the conveyor apron of the mill, in combination with a 25 horizontal revolving drum, which is positioned in a relatively fixed location directly over and adjacent the delivery end of the conveyor of the mill.

These and other objects are accomplished by 30 providing a construction and arrangement of the various parts in the manner hereinafter described and particularly pointed out in the appended claims.

Referring to the drawings:

Fig. 1 is a fragmentary side elevational view, 35 partly in cross section, showing my improved feeding mechanism mounted thereon;

Fig. 2 is a top plan view of the same;

Fig. 3 is a cross sectional view taken on the line 3—3 in Fig. 2; and

40 Fig. 4 is an enlarged cross sectional view of the horizontal revolving drum.

In illustrating one form of my invention I have shown the same in connection with the conventional form of grinding mill, a fragmentary portion 45 of which is shown in Fig. 1 of the drawings. This mill comprises the usual frame 10, mounted on supporting legs 11. Mounted in suitable bearings on the main frame 10 is the usual main shaft 12, on which is mounted the usual cutter head 13.

50 Connected to the forward side of the frame 10 is the usual horizontally extending platform or conveyor trough generally indicated by the reference character 14. This conveyor trough 14 comprises two angle members 15 which are secured to the 55 main frame 10 adjacent the mill proper, while the

other end of the trough is supported on legs not shown. Mounted in the trough 14 is an endless conveyor, generally indicated by the reference character 16. This conveyor comprises a plurality of slats 17. Each of these individual slats are 30 connected with conventional form of chain links 18, which in turn are trained about a sprocket wheel 19 secured to the shaft 20. Secured to the side angle members 15 of trough 14 and extending outwardly and upwardly at a slight angle with 35 respect to the trough, are table extension members 21, which have their forward ends connected by a transverse table member 22. (See Fig. 2.) Secured to the side frame members 15 adjacent the cutter head 13 by means of bolts 23, are side 70 plates 24. Journaled in suitable bearings in the side plates 24, is a shaft 25. Oscillatably mounted on the shaft 25 is a floating feed belt frame 26, which comprises a rearwardly projecting arm 27 and an L shaped bracket 28. Journaled on the 75 free ends of the L shaped bracket 28 are two rollers 29. Secured to the shaft 25 are two spaced apart sprockets (not shown) about which is trained an endless belt 30. This endless belt 30 is trained about the rollers 29 and the sprockets 80 mounted on the shaft 25 (not shown) so as to form in effect a floating feed belt, which is positioned directly over the delivery end of the conveyor belt 16 adjacent the cutter head. The 85 mechanism thus far described covers in a general way, the description of a conventional form of grinding mill heretofore used.

The essential feature of the present invention has to do with a feeding mechanism attachment which is adapted to be attached to the mill above 90 described so as to more efficiently and properly feed fluffy material to the cutter head, such for instance, as hay and the like.

This novel feeding mechanism attachment comprises vertical side plate extensions 31, which are 95 secured by means of bolts of the side plates 24 and to the angle members 15 of the trough 14. Secured to the outside of the angle members 15 and to the outside of the side plate extensions 31 are vertical frame angle members 32, which have 100 their upper ends connected and braced together by means of a transverse bar 33, rotatably mounted in suitable bearing supports above the conveyor apron 16. Adjacent the floating apron 30 is a horizontally revolving drum generally indicated by the reference character 34. This revolving drum comprises external and internal cylindrical members 35 and 36; the cylindrical member 36 being of smaller diameter than the member 35. These cylindrical members are sup- 110

- ported on two oppositely disposed spiders 37 and 38 by means of bolts 39. The spider 38 has formed integrally therewith a bearing sleeve 40, which in turn is journaled in a bearing bracket 5 41 secured to one of the side angle members 32. The sleeve 41 is provided on its outer ends, with a non-circular socket 42, which is adapted in engagement therewith, a complimentary projecting hub 43 formed on the sprocket 44. The sleeve 10 40 and the sprocket wheel 44 are journaled on a stub shaft 45 and are held thereon by a collar 46 secured to the shaft 45 by a pin 47. Secured to the inner end of the stationery stub shaft 45 by means of a pin 48 is an arm 49. The arm 49 extends 15 in a horizontal plane forwardly and has secured thereto by means of another pin 50 a stationary shaft 51. The shaft 51 has its other end supported by a similar arm 52 to which it is secured by means of a pin 53. The other end of 20 the arm 52 is secured to a stub shaft 54 by means of a pin 55. The stub shaft 54 is stationary and is secured by means of a pin 56 to a support bracket 57 which in turn is secured to the other vertical side frame members 32. Mounted on the 25 stationary shaft 51 are a plurality of tines 58 which have eye portions 59 for embracing the shaft 51 and are adapted to extend through apertures 60 formed on the inner cylindrical member 36 of the drum 34. Registering with the apertures 60 are formed in the outer cylindrical member 35, is slotted aperture 61 through which the tines 58 are adapted to reciprocate. From the above description it will be readily understood that the shaft 51 remains stationary and is located eccentric with respect to the axis of the revolving drum 34, so that as the cylinder revolves, these tines are made to project forwardly through the periphery of the drum on the forward side thereof and are withdrawn on the rearward side. 35 40 Each of the tines being withdrawn inwardly sufficiently from the outer cylinder so as to completely strip the hay or other material passing through the machine from the tines. From Fig. 1 of the drawings it will be seen that there are eight sets of tines projecting throughout the periphery of the cylinder and that there are three tines to each set, which are in transverse alignment.
- Cooperating with this horizontal revolving drum, are two oppositely disposed revolving tine members, which are arranged in a slight angle with respect to each other on the opposite sides of the conveyor 17 and located at a point adjacent to the horizontal revolving drum which comprises two bearing brackets 62 secured to the side frame members 15 by means of two transversely extending spaced apart angle members 63. These transverse angle members 63 are secured to the angle members 15 in any well known manner, but preferably by hook bolts (not shown). The bearing brackets 62 are secured to the transverse angle members 63 by means of bolt 64. Formed integrally with each of the bearing brackets 62 are bearing barrels 65 in which are journaled a transverse shaft 66. Secured to one side of the longitudinal center of the shaft 66 is a sprocket wheel 67 which is geared by means of chain 68 to a sprocket 69 secured to the shaft 20. Secured to the outer opposite ends of the shaft 66 are beveled gears 70 which in turn mesh with beveled gears 71. The gears 71 in turn are secured to the shafts 72 located on the opposite sides of the conveyor 16. These shafts are located at an angle with respect to the horizontal conveyor and converge toward their upper ends. The upper ends 75 of the shafts 72 are journaled in bearings 75' secured to angle members 80 hereinafter described. The shafts 72 extend through apertures in the inclined tables 21 as clearly shown in Fig. 2. Secured to each of the shafts 72 and in spaced relation with respect to each other, are plurality of discs or plates 73. Secured to each of these discs 73 by means of bolts 74 are a plurality of curved angularly disposed spring fingers or tines 75. The spring fingers or tines of each of these discs are arranged in substantial vertical alignment and move in unison with respect to each other. Secured to each of the side plate extensions 31 and to each of the vertical members 32 are side wall extensions 76 which have their foremost ends diverging as shown at 78 so as to form a relatively large mouth for the reception of the material being conveyed to the cutter head. See Fig. 2. Each of these side wall extensions 76 and diverging extensions 78 are reinforced by angle members 79 and 80, respectively and are braced across by cross bars 81. The foremost ends of the extensions 78 are secured to vertical supporting angle members 80'. Each of these side wall extensions and diverging extensions 76 and 78 respectively are provided with longitudinally extending slots 100 81 so as to form in effect stripper plates for the spring tines 75 which are adapted to extend therethrough for conveying the material toward the cutter head.
- The power is transmitted from the main shaft 12 of the cutter head to my improved feeding attachment and the various movable elements thereof, by means of a beveled pinion 82 which is secured to the shaft 12 and which in turn meshes with a beveled gear 83 journaled on a stub shaft 84. Formed integrally with the gear 83 is a pinion 85 which in turn meshes with a gear 86 journaled on a stub shaft 87. The gear 86 has a gear 88 formed integrally therewith, which in turn, drives another idler gear 89. The gear 89 in turn has a gear 90 formed integrally therewith which meshes with and operatively drives the gear 91. The gear 91 meshes with a gear 92 secured to the shaft 20 through the medium of 105 which horizontal conveyor belt 16 is driven and also through the medium of which the shaft 66 is driven. Formed integrally with the gear 91 is a sprocket 93 which is geared through the medium of a chain 94 to a sprocket wheel 95 secured 110 to the shaft 25 for driving the floating feed belt 30. Secured to the shaft 25 adjacent the gear 95 is a second sprocket 96 which is geared by means of a chain 97 to the sprocket 98 for driving the revolving drum 34.
- From the above description it will be readily seen that by positioning the rotary tined members at a slight angle inwardly with respect to the vertical, that is, by converging the upper ends of these rotary members, and by positioning a horizontal tined roller in close proximity thereto and forwardly of a floating feed belt that I have provided a very efficient positive means for feeding fluffy material such as hay and the like, to the cutter head of a grinding 135 mechanism and one which will effectively engage and force the material in uniform volume regardless of the height to which it may be piled upon the conveyor trough.
- While in the above specification I have disclosed one embodiment which my invention may assume in practice, it will of course, be understood that the same is capable of modification, and that modification may be made without de- 145
- 150

parting from the spirit and scope of the invention as expressed in the following claims:

What I claim is my invention and desire to secure by Letters Patent is:

5. 1. In a feeding mechanism, the combination with a grinding mill, a cutter head, a horizontal conveyor for feeding the material to said cutter head, a floating feed belt located over the delivery end of said conveyor, a horizontally disposed feed roller having eccentrically actuated fingers projecting through the periphery thereof, said roller located above said horizontal conveyor forwardly of said floating feed belt, two angularly disposed rotating members having substantially radially disposed spring fingers normally extending over the path of said horizontal conveyor, and means for driving said horizontal roller and said rotating members through the shaft of said cutter head.
10. 2. The combination with a grinding mill having a cutter head, a horizontal conveyor, a floating conveyor located over the delivery end of said horizontal conveyor, a rotating feed roller located forwardly of said floating feed belt and above said horizontal conveyor, two oppositely disposed rotating feed members located on the opposite sides of said conveyor and having their axis inclined inwardly toward the upper end thereof for cooperation with said horizontal conveyor for feeding the material to said cutter head.
15. 3. In a feeding mechanism, the combination with a grinding mill, a cutter head, a conveyor for feeding the material to said cutter head, a floating feed belt pivoted over the delivery end of said conveyor, a horizontal feed roller positioned over said horizontal conveyor adjacent said floating feed belt, said horizontal roller having a plurality of reciprocable fingers projecting through the periphery thereof, a plurality of substantially vertically disposed rotating tines located on the opposite sides of said conveyor and extending over the paths of said horizontal conveyor, and substantially vertically disposed stripper plates located on the opposite sides of said conveyor, having slots therebetween through which the tines project for conveying the material to said cutter head.

4. In a feeding mechanism, the combination with a grinding mill, a cutter head, a conveyor for feeding material to said cutter head, a floating feed belt located over the delivery end of said conveyor, two substantially vertically disposed rotating tine members located on the opposite sides of said conveyor, and vertically disposed stationary stripper plates through which tines extend for conveying the material to said cutter head.
80. 5. In a feeding mechanism, the combination with a grinding mill, a cutter head, a conveyor for feeding the material to said cutter head, a floating feed belt located over the delivery end of said conveyor, two substantially vertically disposed rotating members located on the opposite sides of said conveyor adjacent said floating feed belt, curved sprung tines projecting from said rotating members, and extending over the paths of said conveyors, two substantially vertically disposed stripper plates located inwardly of said rotating members through which said tines project, and diverging extending shields forming a continuation of said stripper plates forming a mouth through which the material is fed to said cutter head.
90. 6. In a feeding mechanism, the combination with a grinding mill, a cutter head, conveyor for feeding material into said cutter head, a floating feed belt located over the delivery end of said conveyor, a relatively fixed rotating feed roller mounted on a horizontal axis above said conveyor and forwardly of said floating feed belt, said feed roller having a plurality of reciprocating tines adapted to project through the periphery of said roller, two angularly disposed rotating members located on the opposite sides of said conveyor adjacent said roller, a plurality of curved sprung tines projecting from the axis of said rotary members and extending over the path of said conveyor, and substantially vertically disposed stripper plates located on the inner sides of said rotating members for stripping the material from said tines as the material is conveyed thereby into said cutter head.
